UNITED STATES PATENT OFFICE.

STEPHEN H. GARNER, OF GOLCONDA, ILLINOIS.

NEEDLE-THREADER.

SPECIFICATION forming part of Letters Patent No. 783,692, dated February 28, 1905.

Application filed November 3, 1904. Serial No. 231,246.

To all whom it may concern:

Be it known that I, STEPHEN H. GARNER, a citizen of the United States, residing at Golconda, in the county of Pope and State of Illinois, have invented a new and useful Needle-Threader, of which the following is a specification.

This invention relates to devices for facilitating the threading of needles, ripping the seams of garments, and for similar purposes, and has for its object to provide a simply-constructed and easily applied and operated device of this character preferably attachable to a sewing-thimble.

With these and other objects in view, which will appear as the nature of the invention is better understood, the same consists in certain novel features of construction, as herein-after fully described and claimed.

In the accompanying drawings, forming a part of this specification, and in which corresponding parts are denoted by like designating characters, is illustrated the preferred form of embodiment of the invention capable of carrying the same into practical operation, it being understood that the invention is not necessarily limited thereto, as various changes in the shape, proportions, and general assemblage of the parts may be resorted to without departing from the principle of the invention or sacrificing any of its advantages.

In the accompanying drawings, Figure 1 is a side view of the improved device applied to a sewing-thimble. Fig. 2 is a similar view, enlarged, with the ripping-blade extended. Fig. 3 is a plan view with the ripping-blade depressed. Fig. 4 is a section on the line 4-4 of Fig. 2. Fig. 5 is a perspective view, on the same scale as Figs. 3 and 4, of the supporting-frame detached. Fig. 6 is a view of the combined threading-hook and blade-locking member detached.

The improved implement comprises a supporting member having spaced sides 10 11 and preferably connected by an integral web 12, extending along one side for a portion of the distance, leaving the side portions disconnected for a part of their lengths and with the open ends diverging, as at 13 14, said side

portions constituting spring clamping-jaws to hold a needle therebetween.

Resting in the space between the side members is a resilient wire rod 15, extended at one end for position opposite the diverging ends 13 14 and terminating in a lateral hook 16 and with the other end bent laterally, as at 17.

The rod 15 is provided with two intermediate offsets 18 19, one to engage the inner end of the web 12 and the other to cause a portion of the rod to be spaced from the web to form a supporting-spring for a ripping-blade 20, pivoted at 21 between the side portions 10 11. The ripping-blade is also provided with a shoulder 22, into which the end of the lateral bend 17 of the rod 15 fits, as shown in Fig. 2, when the blade is distended to limit its outward movement.

The side members 10 11 will be pinched upon the portion of the rod 15 between the intermediate shoulders 18 19 to prevent its removal laterally therefrom, while the engagement of the offset 18 with the web 12 prevents longitudinal movement in one direction and the laterally-bent end 17, bearing constantly against the ripping-blade 20, prevents longitudinal movement in the opposite direction. The rod 15 is thus firmly held in position and will not be displaced under the strains to which it will be subjected while in use.

It will here be explained that as the wire rod or bar 15 is fixed intermediate of its ends its rear offset portion is free and operates as a spring-bar across the inner end and one longitudinal edge of the blade 20 in both the closed and open positions of the latter, whereby the spring operates to yieldably hold the blade at its opposite limits, so as to prevent accidental pivotal movements thereof, while at the same time permitting of the convenient opening and closing of the blade.

The hooked terminal 16 of the rod 15 is reduced in size to enable it to pass through the eye of the needle to be threaded.

To thread a needle with the improved device, the needle is positioned between the diverging ends 13 14 of the needle-holding jaws, with the eye of the same receiving the reduced hooked end 16 of the rod and the thread

drawn over the protruding portion in the rear of the hook 16. The needle is then detached from the rod, the hook 16 drawing the thread which it holds through the eye of the needle 5 and completing the threading action, as will be obvious.

The rod 15 will necessarily be of fine steel, preferably oil-tempered, to secure the requisite strength and resiliency and will be small 10 enough to pass through the eyes of the smallest needles.

The supporting member will preferably be attached to a sewing-thimble 24 and when thus employed produces a very convenient, 15 useful, and efficient device.

The end 13 of the member 10 is curved to a greater extent than the opposite side 14 when applied to a thimble, so that it conforms 20 to the shape of the same and offers a more effectual guide to the needle, and at the same time the longer portion 13 prevents any tendency of the needle to miss the space between the side members when the device is applied to open-topped thimbles.

25 Having thus described the invention, what is claimed is—

1. A needle-threader comprising spaced side members, a ripping-blade pivoted between the same, and a rod supported intermediate of 30 its ends between the side members, one end of the rod being provided with a lateral bend constituting a spring portion bearing against the blade to limit the movement thereof, and the other end of the bar being provided with 35 a thread-engaging hook for passing through the eye of a needle supported between the side members.

2. A needle-threader comprising spaced side members which are extended to form 40 spring needle-holding jaws diverged at their outer ends, a ripping-blade pivoted between the side members and foldable therebetween toward the outer ends of the jaws, and a resilient bar held between the members with 45 one end bent laterally to bear against the pivotal end of the blade to limit the movement thereof, the other end of the bar being provided with a thread-engaging hook disposed at one side of and opposite the space 50 between the diverged end portions of the jaws and adapted to pass through the eye of a needle supported between the jaws.

3. A needle-threader comprising spaced side members, a ripping-blade pivoted between 55 the members, and a resilient wire held intermediate of its ends between the members, one end portion of the wire constituting a spring bearing against the pivotal end portion of the blade and provided with a lateral terminal 60 bend also engaging the blade to limit its opening movement, the other end of the wire

being provided with a thread-engaging hook for passing through the eye of a needle supported between the side members.

4. A needle-threader comprising spaced 65 side members connected by a transverse web extending part way only of the lengths of the side members, the unconnected portions of the side members being diverged at their free ends and constituting needle-holding jaws, a 70 ripping-blade pivoted between the members, and a wire supported upon the web between the side members and provided with intermediate spaced offsets, one of said offsets lying against the web and the other offset constituting a spring bearing against the inner end of the blade, the opposite end of the wire being disposed opposite the space between the jaws and terminating in a thread-engaging hook. 75

5. A needle-threader comprising a pair of 80 spaced side members connected throughout a part of their lengths by a laterally-offset web, the remaining portions of said sides constituting needle-holding jaws, and a bar secured between the members upon the web with one 85 end portion terminating in a thread-engaging hook disposed at one side of and in alinement with the space between the needle-holding jaws.

6. A needle-threader comprising a pair of 90 spaced sides having corresponding end portions constituting needle-holding jaws, a longitudinally-disposed bar offset from the device opposite the space between the jaws and terminating in a thread-engaging hook, and a 95 ripping-blade pivoted between the members and working at that side of the latter opposite the bar.

7. A thimble provided with a terminally-hooked needle-threading bar disposed longitudinally thereof and offset laterally therefrom, the hooked end of the bar being directed toward the closed end of the thimble. 100

8. A thimble provided with a pair of spaced longitudinally-disposed side members having 105 their end portions adjacent the closed end of the thimble constituting needle-holding jaws, a bar carried by the side members and offset laterally therefrom with one end portion disposed opposite the space between the jaws 110 and terminating in a thread-engaging hook, and a ripping-blade pivoted between the members and working at that side thereof opposite the bar.

In testimony that I claim the foregoing as 115 my own I have hereto affixed my signature in the presence of two witnesses.

STEPHEN H. GARNER.
